Patented July 13, 1909.

UNITED STATES PATENT OFFICE.

EMMA DONNER, OF PEORIA, ILLINOIS.

DEVICE FOR CARRYING MATTRESSES.

No. 927,506.

Specification of Letters Patent.

Patented July 13, 1909.

Application filed June 19, 1908. Serial No. 439,340.

To all whom it may concern:

Be it known that I, EMMA DONNER, citizen of the United States, residing at Peoria, in the county of Peoria and State of Illinois, have invented certain new and useful Improvements in Devices for Carrying Mattresses; and I do hereby declare that the following is a full, clear, and exact description of the invention, which will enable others skilled in the art to which it appertains to make and use the same.

This invention relates to a device for carrying, and for airing mattresses.

The object of this invention is to provide a simple and light device upon which the mattress may be placed to air and which may be folded with the mattress therein so that the latter may be easily carried from place to place.

Mattresses are usually very bulky and unwieldy and in view of this it is my purpose to furnish a device by which they may be easily handled and also that they may be easily aired and that they may be held above the ground so that the air can reach them on all sides. A mattress of considerable weight can be readily carried by one person if it can be properly laid hold of and the device to be described easily admits of this.

In the appended drawing, Figure 1 is a plan of my device. Fig. 2 is a side elevation showing one of its frame members partly raised and indicating in broken lines the folded position of the device. Fig. 3 shows a portion of a frame member and a hook to engage it. Fig. 4 is a transverse section of a portion of the device on line X X Fig. 2. Fig. 5 is a view of a portion of a frame member shown in Fig. 2 and a hooked arm adapted to engage therewith.

In the figures the letters A A indicate two horizontally disposed side members secured to and supported by legs B B, and whose extremities extend beyond the legs as shown in Fig. 2 at C C. The side members A A are spaced apart by two horizontally disposed slats D D having their ends turned down at right angles as at E and secured to the members A A by means of rivets or other suit-

able devices F. The said legs B B extend some distance above the members A A and pivoted thereto are the extremities G of two U-shaped frames H. Secured between and to the said extremities G are two slats J which are preferably the same height as the slats D D as clearly shown in Fig. 2 in which one of the said slats D and one of the slats J are shown in section to make this understood.

Pivoted to each of the members G of the frames H is a leg K. To each leg at L is pivoted one end of a link M whose other end is pivoted to the projecting end C of a member A by means of a rivet N. On one of the frames H is an eye O and on the opposite frame is pivoted an arm P having at its free end a hook Q adapted to engage the said eye when the two frames H H are placed in a folding position parallel to one another as shown by the dotted lines in Fig. 2; the eye and the arm with its hook being clearly shown in Fig. 3. Upon each said member G of one of the frames H is pivoted an arm R having a hook at its free end adapted to engage a pin T projecting from each of the side members G of the opposite frame H. The hook S just described is provided with a bevel S' so that when it meets the pin T the hook will be sprung outward and in regaining its normal position will engage said pin as shown in Fig. 5; the neck by which the hook is connected with the arm R being sufficiently flexible to permit this while at the same time it is perfectly strong.

As shown in Fig. 2 the two end portions or frames H are adapted to raise to a vertical folded position and it will be noted that the pivotal relation of the parts is such that the legs K, the frames H, and the links M readily fold together to make a compact form of device. The arm R serves to hook the frames together at the top but its more important mission is to hold the mattress in place. The arm R at each end serves to hook the frames together and serves also as hand rails by which the device may be carried; the pin T and the hook S being provided to lock the arm for this purpose and

a person at each end can readily carry the device with the mattress therein by means of said arms.

In the practical use of my device, it is placed in its open position at the side of the bed whose mattress is to be handled, its slats being preferably the same height as the springs on which the mattress rests so that said mattress may be readily slipped off the springs upon the said slats. The frames H are then raised parallel to one another thus folding the ends of the mattress together. The arms P and R are then hooked as already described and the device is ready. After carrying it out of doors the said arms P and R are released and the frames H lowered to the flat or horizontal position to permit the mattress to lie flat.

It is to be observed that the end legs K are curved inwardly at their upper ends from the pivot at L to the point of connection with the member G. This is done in order that all the members G, K, M will lie parallel to one another in close order so that there will be no projecting parts that will be in the way or cause trouble in passing through narrow doorways or passages.

The device may be made of light wood whose parts are properly secured together by means of rivets or bolts or it may be constructed of light weight of iron-work as may be best adapted for the purpose.

I have described my device as I prefer to construct it but I desire to make it understood that I may change it in various ways without departing from the spirit and intent of the invention.

Having thus described my invention, I claim:—

1. In a device for carrying mattresses, a middle frame portion comprising four standards, a separate bar attached to each of two opposite pairs of said standards, the same being placed below the upper ends of the standards each said bar projecting beyond each leg of the pair to which it is attached, a horizontally disposed cross member secured to and connecting the two bars, a separate member pivotally attached at one of its ends to one of the projecting ends of each bar, a standard pivotally attached between its ends to the free end of each of the said members, a single upper frame portion pivotally attached at its ends to the upper free extremity of two opposite standards of the pairs of standards first described and having the upper ends of the last described standards pivoted thereto, the said frame portions adapted to fold parallel to one another, cross supporting members secured to both the latter, coöperating latch members carried by said frame portions for holding them in their folded positions.

2. In a device for carrying mattresses, a middle frame portion comprising four stand-

ards, a separate bar attached to each of two opposite pairs of said standards the same being placed below the upper ends of the standards, each said bar projecting beyond each leg of the pair to which it is attached, a horizontally disposed cross member secured to and connecting the two bars, a separate member pivotally attached at one of its ends to one of the projecting ends of each bar, a standard pivotally attached between its ends to the free end of each of the said members and having its upper portion curved substantially as shown, a single upper frame portion pivotally attached at its ends to the upper free extremity of two opposite standards of the pairs of standards first described and having the upper ends of the last described standards pivoted thereto, the said frame portions adapted to fold parallel to one another, cross supporting members secured to both the latter, and coöperating latch members carried by said frame portions for holding them in their folded positions.

3. In a device for carrying mattresses, a middle frame portion comprising four standards, a separate bar attached to each of two opposite pairs of said standards the same being placed below the upper ends of the standards, each said bar projecting beyond each leg of the pair to which it is attached, a horizontally disposed cross member secured to and connecting the two bars, a separate member pivotally attached at one of its ends to one of the projecting ends of each bar, a standard pivotally attached between its ends to the free end of each of the said members, and having its upper portion curved substantially as shown, a single upper frame portion pivotally attached at its ends to the upper free extremity of two opposite standards of the pairs of standards first described and having the upper ends of the last described standards pivoted thereto, the said frame portions adapted to fold parallel to one another, cross supporting members secured to both the latter, coöperating latch members carried by said frame portions for holding them in their folded positions, and coöperating latch portions at each side of the two frame portions to hold the mattress in place when the device is folded.

4. In a device for carrying mattresses, a middle frame portion comprising four standards, a separate bar attached to each of two opposite pairs of said standards, the same being placed below the upper ends of the standards, each said bar projecting beyond each leg of the pair to which it is attached, a horizontally disposed cross member secured to and connecting the two bars, a separate member pivotally attached at one of its ends to one of the projecting ends of each bar, a standard pivotally attached between its ends to the free end of each of the said members,

and having its upper portion curved substantially as shown, a single upper frame portion pivotally attached at its ends to the upper free extremity of two opposite standards of the pairs of standards first described and having the upper ends of the last described standards pivoted thereto, the said frame portions adapted to fold parallel to one another, cross supporting members secured to both the latter, and coöperating

latch portions at each side of the two frame portions to hold the mattress in place when the device is folded.

In testimony whereof I affix my signature, in presence of two witnesses.

EMMA DONNER.
